UNITED STATES PATENT OFFICE

DAVID E. JACKSON, OF OLYMPIA, WASHINGTON

WASHING MACHINE

Application filed April 3, 1928. Serial No. 267,025.

This invention relates to clothes washing machines and one of the primary objects of this invention is to provide novel means in a washing machine for receiving different classes of clothes to be washed, whereby one class will not be mingled with another, thereby preventing dyes from one fabric from running into another, and the like.

Another salient feature of the invention is to provide a washing machine having a novel type of tub, the tub being provided with a plurality of independent compartments for receiving different classes of clothes, such as linen, colored fabrics, fine underclothing and the like.

A further important object of the invention is the provision of novel means for introducing water into each of the independent compartments and novel means for draining each of the compartments from a single outlet or drain.

A further object of the invention is the provision of novel means for incorporating a bluing cup within the water supply line, whereby the bluing can be introduced into the different compartments with the clean water supply.

A still further object of the invention is to provide a washing machine designed to wash all sorts and colors of clothes during a single operation of the machine which will be durable and efficient in use, one that will be simple and easy to manufacture and one that can be placed upon the market at a reasonable cost.

With these and other objects in view, the invention consists in the novel construction, arrangement and formation of parts, as will be hereinafter more specifically described, claimed, and illustrated in the accompanying drawings, in which drawings,

Figure 1 is a side elevation of the novel tub of the washing machine, the tub being partly broken away and in section to illustrate the interior construction thereof;

Figure 2 is an end elevation of the novel tub;

Figure 3 is a horizontal section through the tub taken on the line 3—3 of Figure 1, looking in the direction of the arrows,

Figure 4 is a transverse section through the tub taken on the line 4—4 of Figure 1, looking in the direction of the arrows,

Figure 5 is a detail horizontal section taken on the line 5—5 of Figure 1 looking in the direction of the arrows illustrating the arrangement of the novel drain,

Figure 6 is a further detail horizontal section taken on line 6—6 of Figure 1 illustrating the novel drain, and Figure 7 is a detail vertical section illustrating the arrangement of the water supply for the tub and the means of incorporating the bluing cup with said water supply.

Referring to the drawings in detail, wherein similar reference characters designate corresponding parts throughout the several views, the letter A generally indicates the improved tub, which comprises an elongated body 10 formed from any desired material, such as copper, galvanized iron, or the like.

As shown, the tub 10 is of a substantially cylindrical form provided at its upper end with a top plate 11 provided with openings 12 which are adapted to be closed by suitable water tight covers (not shown).

In accordance with this invention, the tub 10 is divided into a plurality of compartments 13, 14, 15 and 16, by partition plates 17, 18, and 19. As shown, these partition plates extend transversely of the hub and are equidistantly spaced so that the compartments will be of equal size. It is to be noted, however, that the partitions can be spaced different distances apart so that different sized compartments can be provided.

The opposite end walls 20 of the tub A are provided with trunnions 21 and 22 and the tub is supported by these trunnions in the ordinary manner so as to permit the oscillation thereof in the ordinary way.

It is to be noted, however, that the trunnion 22 is of a hollow formation and this trunnion forms a part of the invention and provides means for permitting a supply of water to be delivered to the different compartments. A water supply hose 23 can be connected with the hollow trunnion and this trunnion is provided with an outlet nipple 24 to which is

connected the delivery pipe 25 for the compartment.

Extending longitudinally of the tub is a pipe 26 and this pipe can extend through 5 the different partitions 17, 18 and 19 and the portions of the pipe in the different compartments are provided with perforations 27 to permit the flow of water from the pipe into the compartments. The pipe 26 is connected 10 to the pipe 25 by the medium of an elbow 28. A valve 29 arranged in the pipe 25, permits the supply of water to the compartments 13-15 to be shut off without opening the cover of the tub 10. If desired, valves 15 29a may be arranged in the pipe 26 within the compartments 13-15, and these valves and the valve 29 permit the amount of water supplied to the respective compartments 13-15, to be regulated and controlled.

20 It is obvious from the description so far that clean water can be readily introduced into the compartment.

In order to permit the bluing of the clothes without the necessity of taking the clothes 25 out of the tub and placing the same in bluing water, I provide a bluing cup 30 which can be connected directly with the hollow trunnion 22 and it is obvious that this cup can be filled with bluing and the flow of water 30 through the pipe 22 will carry a certain percentage of the bluing therewith.

Another important feature of the invention is the novel arrangement of the drain for the compartments 13, 14, 15 and 16, and 35 in this connection, it is to be noted that the body of the tub 10 is provided with an interior false bottom or plate 31 which forms a false bottom for each of the compartments.

Between the false bottom of plate 31 and 40 the main bottom of the tub is provided a chamber 32 into which the water from the compartments 13 and 16 is adapted to drain and the false bottom is provided with longitudinal rows of perforations 33 to provide 45 the drain openings.

In accordance with this invention, I provide a main drain plug 34 which is located centrally within the tub between the main bottom thereof and the false bottom 31.

50 This main drain plug 34 is provided with an outlet nipple 35 which protrudes through the main wall of the tub and this nipple has connected thereto a drain pipe or hose 36.

It is to be noted that the main drain plug 55 34 is provided with upper and lower sets of openings 37 and 38 for a purpose which will be later described.

Arranged directly below the two central compartments 14 and 15 in the side drain 60 compartment 32 are drain chambers 39 which are spaced from the main bottom wall of the tub. These chambers communicate with the compartments 14 and 15 and with the drain plug 34 through the upper set of openings 37 65 and the chambers 39 are so formed as to per-

mit the water draining from the compartments 13 and 16 to communicate with the lower openings 38. It is to be noted that the chambers 39 include flat lower walls 40 and side walls 41. The lower walls have their 70 outer edges secured to the tub at their point of connection of the false bottom therewith, while the side walls 41 are secured to the false bottom defining in connection therewith the side chambers 39. These side walls 41 gradually converge toward the drain plug and are secured thereto and define between the same a passageway which communicates with the chamber 32 and with the chambers 13 and 16 below the false bottom 31 by means of openings 42 in the partition plates 17 and 19.

By this construction, the water draining from the compartments 14 and 15 is kept separate from the water draining from the compartments 13 and 16. This is desirable in 85 view of the fact that different classes of fabrics are placed in the compartments 14 and 15 from the compartments 13 and 16 and it is not desirable that the water from the different compartments commingle until the same 90 reaches the drain plug.

The tub is oscillated back and forth in the usual way and the essence of the invention consists in the formation of the different compartments 13, 14, 15 and 16 and the means for introducing and draining water from the said compartments. Thus, as stated, the compartments are adapted to receive different types and classes of clothes so that these clothes can be treated in different ways in a 100 single washing operation. For instance, colored fabrics can be placed in one compartment so that dyes therefrom will not injure fabrics in another compartment. Also linens can be placed in another compartment, ordinary clothes in a third compartment, and fragile fabrics, such as silk and the like, in a fourth compartment.

105 This permits the washing of a number of different classes of clothes all in one operation thereby permitting an entire wash to be handled in a minimum amount of time and with a minimum amount of labor.

Changes in details may be made without departing from the spirit or the scope of this 115 invention but:

What I claim as new is:

In a clothes washing machine, a tub, a plurality of partitions arranged in said tub defining a plurality of independent clothes receiving compartments, a false bottom for each compartment defining in connection with the bottom wall of the tub a drain receiving compartment, each of the false bottoms having a plurality of drain openings therein, a centrally disposed drain plug in the bottom wall having upper and lower drain openings therein, a drain nipple carried by said plug extending exteriorly of the tub, the lower set of drain openings communicating with the 130

drain compartment and certain of the clothes compartments, and drain chambers arranged in the drain compartment communicating with others of the clothes compartments and
5 having communication with the upper set of drain openings in said plug.

In testimony whereof I affix my signature.
DAVID E. JACKSON.
